UNITED STATES PATENT OFFICE.

PAULUS J. A. VAN DEINSE, OF GREENVILLE, MICHIGAN.

HOLLOW BLAST-GRADE.

1,189,888

Specification of Letters Patent.

Patented July 4, 1916.

Application filed December 27, 1910. Serial No. 599,615.

To all whom it may concern:

Be it known that I, PAULUS J. A. VAN DEINSE, a citizen of the United States, residing at Greenville, in the county of Montcalm and State of Michigan, have invented a new and useful Hollow Blast-Grate, of which the following is a specification.

This invention has reference to improvements in grates wherein alternate blast and draft bars are employed, and the object of the present invention is to provide a structure wherein there is little or no likelihood of the streams of air issuing from the blast bars being diverted through the draft bars, or between them and the draft bars toward the ash pit, or the blast outlets becoming choked, or the blast bars becoming filled to any material extent with ashes so as to reduce their effective cross-sectional area. Furthermore, in the present invention the bars are well protected from damage due to the efforts of heat, the blast outlets may be made to diffuse the blast, if desired, and the automatic removal of ashes from the grate through the draft bars is facilitated.

In accordance with the present invention the blast bars have rigid or corrugated fuel sustaining surfaces with blast openings of appropriate shape in the ridges; while the draft bars are similarly shaped with openings in the valleys, while the meeting edges of the two types of bars are preferably so formed with respect one to the other that there is no likelihood of the blast streams finding escape therethrough rather than through the bed of fuel.

The invention will be best understood from a consideration of the following detailed description, taken in connection with the accompanying drawings forming a part of this specification, with the understanding, however, that the showing of the drawings is in part indicative and does not necessarily confine the invention to the exact structure shown, since various modifications may be made in the structure to adapt the grate to different types of fuel while the salient points of the invention are still retained.

In the drawings:—Figure 1 is a plan view of associated blast and draft bars, a single blast bar and a single draft bar only being shown. Fig. 2 is a section on the line 2—2 of Fig. 1. Fig. 2^a is a detailed section of a modified form. Fig. 3 is a section of associated draft and blast bars showing a

slightly modified construction. Fig. 4 is a bottom plan view of a blast grate bar. Fig. 5 is a section on the line 5—5 of Fig. 4.

Referring to the drawings, there is shown a blast bar A and a draft bar B. In the particular structure shown the blast bar comprises a top member 1, a bottom member 2, and side members 3 joining the top and bottom members, and suitable end walls 4 are provided whereby the blast bar is formed with an interior chamber into which the air under pressure may be directed. In the particular structure shown, the side members 3 approach toward the bottom 2, but this is not a mandatory form.

The top 1 is shown as corrugated, the corrugations running longitudinally of the bar, but it will be understood that any form of upper surface may be adopted, whereby there are formed ridges 5 and valleys 6, whether the ridges be lengthwise of the bar or extend in any other direction, such changes over the showing of the drawing being determined by the particular conditions to be met, since some kinds of fuel require different forms of grate bars than others. The blast bar A is provided with series of perforations 7 shown in Fig. 2 as of equal diameter throughout, and in Fig. 2^a as tapering toward the upper end, and these perforations may be circular or any other desired shape, the particular form of the passages 7 being determined by the conditions to be met, passages 7 with circular outlets answering for certain kinds of fuel, while outlets of other shapes are advantageous with fuel of other kinds, and in some instances those of equal diameter throughout are to be preferred and under other conditions those of greater diameter at one end than the other are preferable, but in any instance the outlets of the passages 7 are located at the highest points of the ridges 5 whatever be the shape of such passages and outlets. By preference the passages 7 in one ridge 5 alternate with the passages 7 in the next adjacent ridge or ridges, but even in this respect the particular arrangement is not mandatory.

The draft bars B have each a top member 8 and side members 9 with transverse webs 10 where needed for strength, but these bars have no bottom member. The draft bars B also have the top member 8 corrugated or otherwise formed to produce ridges 11 and valleys 12 between them. The contour of

the fuel supporting surface of the bars B may correspond to that of the bars A or may differ, but instead of having passages opening at the tops of the ridges, each 5 draft bar B has passages 13 opening at the lowest point of the valleys. The openings 13 are in spaced relation one to the other in each valley, and those of one valley may alternate with those of the next adjacent 10 valley or valleys, but this arrangement is not mandatory though efficient in practice. Moreover, it is advisable, though not necessary, that the series of passages 7 adjacent the edge of a blast bar should have the 15 passages alternate with the adjacent passages of the next draft bar in order.

The passages 7 in Fig. 2 are shown as of equal diameter throughout their length, while the blast bar A of Fig. 3 is shown 20 with passages 7^a having the exit opening 14 expanded. Here again the relative size and shape of the blast passage will depend upon the fuel to be used. In the structure of Fig. 2 the blast is directed in a condensed 25 stream into the fuel. In Fig. 3 the blast is permitted to expand at the end of the blast passage toward the fuel, and consequently enters the latter in an expanding stream. These two forms of blast passages together 30 with that shown in Fig. 2^a may be taken as typical of any suitable form as may be found expedient for the kind of fuel used.

Since the body of fuel on the grate offers resistance to the passage of the blast where 35 the grate is overloaded, the streams issuing from those passages 7 or 7^a adjacent the longitudinal edge of the blast bar may find their way through the spaces between the blast bar and the next adjacent draft bar, 40 the streams naturally following the path of least resistance. To overcome this, the blast and draft bars may be provided with lap joints where meeting. For this purpose the blast bar A of Fig. 2 is shown as provided 45 with a longitudinal flange 15, while the draft bar has a corresponding recess or groove 16, and the said draft bar may have a longitudinal flange 17 underriding the flange 15, while the blast bar is provided 50 with a matching groove 18 adapted to receive the flange 17. This will form an overlapping joint through which little or no air will find its way from the blast openings adjacent to the joint. Under some circumstances a plain butt joint may be provided 55 between the two bars A and B, as indicated at 19^a in Fig. 3. These two types of joint may be taken as indicative of any suitable joint structure between the two types of 60 bars.

By locating the blast passages at the tops of the ridges the danger of choking these passages with ashes or particles of fuel, and the likelihood of ashes or other matter 65 reaching the interior of the blast bar, are

reduced to a minimum. Another great advantage of so locating the blast passages is that if the valleys become filled with ashes, which, being an excellent non-conductor of heat, protects the top of the bar, thereby 70 increasing its durability. If the outlets were located in the valleys or in the inclined faces, the parts adjacent to or opposite the outlets would become intensely hot, since the action of the blast is that of a 75 blow-pipe.

In a hollow blast grate the draft bars are designed primarily for the escape of ashes through them, and consequently the passages 13 expand toward the lower end, so 80 that particles of ashes find no lodgment therein, but any ashes which enter the passage 13 will fall therethrough to the ash pit, the bottom of the draft bar being open. Moreover, the passages 13 are located in the 85 valleys between the ridges, and the ashes naturally gravitate to these points. The draft bars become covered with ashes, so that the valleys are filled therewith, the ashes forming a sort of protective coating 90 as in the blast bars. In the case of the draft bars the passages 13 may further even become temporarily bridged over with ashes, thus preventing any material loss of the air streams by diversion through the draft bars. 95

The openings through the blast bars are solely for the purpose of introducing air and by forming them through the ridges, so as to open at the tops of such ridges, they are kept markedly free from ashes. In 100 the draft bars the openings are for the disposal of ashes, and are so located and of such shape as to facilitate the directing of the ashes to the openings and the passage of such ashes through the openings. 105

Each blast bar is formed with a passage 19 through the bottom wall 2, and this passage is surrounded with a nipple 20, cored out as shown at 22 to form an annular shoulder or flange 23 which may be reamed out to snugly fit a tube 24 abutting against the bottom 2 at the opening 19, the interior of the tube and the opening 19 being of the same diameter. This is the preferred form of inlet for the blast bar but other means for introducing the air into the blast bar may be used. The bottom 2 has another opening 25 preferably remote from the inlet 19, and this opening 25 is normally covered by a slide 26 held to the bar by a guide plate 27 fast to the bottom 2 of the blast bar and provided with a passage 28 matching the opening 25. The slide 26 has fast thereto an eye 29 near one end normally within a recess 30 in the corresponding end of the plate 27, while a stop pin 31 projecting from the bottom 2 limits the movement of the slide to uncover the opening 25. The slide 26 is moved to the open position when it is desired to blow out accumulations from the blast bar. 125

What is claimed is:—

1. A grate composed of blast bars and draft bars in alternation, each having the fuel supporting surface formed with alternate ridges and valleys, the blast bars having air passages therethrough opening at the highest points of the ridges, and the draft bars having passages therethrough opening at the bottoms of the valleys. 5
10. 2. A grate composed of blast bars and draft bars in alternation each having the fuel supporting surface formed with alternate ridges and valleys, the blast bars having air passages therethrough opening at the highest points of the ridges, and the draft bars having passages therethrough opening at the bottoms of the valleys, the meeting edges of the blast and draft bars being in overlapping relation. 15
20. 3. A grate composed of blast bars and draft bars in alternation, each having the fuel supporting surface formed with alternate ridges and valleys, the blast bars having air passages therethrough opening at the highest points of the ridges, and the draft bars having passages therethrough opening at the bottoms of the valleys, the meeting edges of the blast and draft bars being formed with matching longitudinal flanges 25 and grooves, the flange of one bar seating in the matching groove of the other bar. 30
4. In a blast grate, a blast bar having its fuel sustaining surface provided with alternating ridges and valleys and having blast passages with their exit openings at the 35
- highest points of the ridges and each there expanding to direct an expanded stream of air into the fuel. 40
5. A grate composed of blast bars and draft bars in alternation and having the fuel sustaining surface formed into alternate ridges and valleys, the blast bars having air passages therethrough opening at the summits only of the ridges and the draft bars having openings therethrough at the bottoms only of the valleys. 45
6. A blast grate comprising alternate blast and draft bars each having the fuel sustaining surface formed into alternate ridges and valleys, each blast bar having series of passages through its fuel sustaining surface opening at the summits only of the ridges, and each draft bar having openings through its fuel sustaining surface at the bottoms only of the valleys, the openings through the draft bars expanding in a direction away 50 from the fuel sustaining surface. 55
7. A grate composed of blast bars and draft bars in alternation and having the fuel sustaining surface formed into alternate ridges and valleys, the blast bars having air passages therethrough opening at the summits of the ridges. 60

In testimony, that I claim the foregoing as my own, I have hereto affixed my signature in the presence of two witnesses.
